UNITED STATES PATENT OFFICE.

HYLA F. MAYNES, OF GAINES, PENNSYLVANIA.

CLOTHES-LINE-EXTENSION DEVICE.

945,337.

Specification of Letters Patent. Patented Jan. 4, 1910.

Application filed December 7, 1908. Serial No. 466,392.

To all whom it may concern:

Be it known that I, HYLA F. MAYNES, a citizen of the United States of America, and a resident of Gaines, county of Tioga, and State of Pennsylvania, have invented certain new and useful Improvements in Clothes - Line - Extension Devices, of which the following is a specification, reference being had to the accompanying drawings, forming a part thereof.

My invention relates to improvements in extension devices for clothes lines of the type in which a portion of a clothes line which is normally located on the outside of a building may be drawn into a room through the window thereof, so that the clothes line may be manipulated, and the clothes hung thereon and removed therefrom, within a room thereby avoiding the necessity of the operator leaning out of the window.

The main object of my invention is to provide an extension device such as will permit the free use of the clothes line in any of its positions, as when fully extended or when in its extreme opposite position or in any intermediate position, and also to provide that there shall be no substantial movement of the main body portion of the clothes line when the extension device is manipulated.

In order that my invention may be fully understood, I will now proceed to describe an embodiment thereof, having reference to the accompanying drawings illustrating the same, and will then point out the novel features in claims.

In the drawings, Figure 1 is a view in side elevation showing a clothes line extension device embodying my invention, the same being illustrated as attached to a building, and adjusted to a position partly within a room thereof. Fig. 2 is a similar view showing the extension device as adjusted to a position wholly without the building. Fig. 3 is a top view of the extension device, and Fig. 4 is a detail view in transverse section upon the plane of the line 4—4 of Fig. 3.

The extension device comprises, in general, a slide 10 having pulleys 11—12 at opposite ends thereof, a guide 13 provided with a slot or guide-way in which the slide is mounted, and a relatively stationary pulley 14 mounted upon a fixed support, preferably upon the side of the guide, as shown in the drawings. The axes of the pulleys 11, 12, and 14 are parallel with each other

and those of the pulleys 11 and 12 are arranged in a single horizontal plane parallel with the slide 10. The axis of the pulley 14 is also preferably in the same plane, but is not necessarily so.

The usual distant pulley 15 is provided, the same being supported by some stationary part at a suitable distance from the building such as a clothes pole. The clothes line 16 passes over the distant pulley 15, thence around the stationary pulley 14, thence over the two pulleys 11 and 12 at opposite ends of the slide 10, and thence back to the distant pulley 15. The guide 13 is carried by a bracket 17, which is secured to the outside of a building 18, in proximity to the window thereof. Preferably the guide and bracket are connected together by means of a vertical pivot pin 20 whereby the said guide may be swung horizontally about the said pivot, notches or teeth 21 being provided for the purpose of preventing such movement except when desired. When it is desired to make an adjustment, a nut 22 upon the central pivot pin may be slackened and the parts properly adjusted, and thereafter upon the tightening of the nut, further movement will be prevented.

The normal position of the device is shown in Fig. 1 of the drawings. When it is desired to manipulate the line from within the building 18, the window 19 having been opened, the operator draws the slide 10 into the room; this may readily be done by grasping a hand piece 23 which is provided for the purpose. In Fig. 2, I have shown the slide as partially drawn into the room and the clothes line may be manipulated from such position or the slide may be drawn all the way in, if preferred. When the slide has been properly adjusted, the clothes line is manipulated from the lower strand thereof, the clothes being hung thereon within the building and then the line caused to travel in a direction to carry the clothes out of the window, all in a manner which will be readily understood by reference to the drawings.

Similarly the clothes may be drawn into the room by pulling upon the lower strand of the rope, and the clothes then removed from the line at a point within the building. It will be noticed that the manipulation of the slide in no way affects the position of the body portion of the line nor does it produce any slack in the line because, while one portion of the line is being paid off at one end,

an equal portion of the line is being picked up at the other end thereof, and it will also be readily understood that the tension upon the line produced by the hanging of the clothes in no way tends to move the slide either in or out of the room because the said tension is equalized upon opposite ends of the slide. It is therefore unnecessary to provide any means for locking the slide in any 10 position in which it is adjusted.

It will be observed that by arranging the axes of the two pulleys 11 and 12 in the same horizontal plane the rope may be so disposed as to largely reduce the tendency of the slide 15 to tip when the rope is pulled, and consequently the slide will have less tendency to bind in the guide than might otherwise be the case. In order to take the weight off the extension device when it is to be manipulated, I have provided a hook 24 for temporarily supporting the clothes line at that point if such be desired. Under ordinary circumstances this hook is not necessary, but where the line is of great length and the 20 slide of considerable length with relation to the guide in which it is carried, the use of such a tension supporting device might be advantageous; at no times would it be necessary, however, to use such a hook except 25 while the slide is actually being moved. I have shown this hook as located upon the guide piece 13 itself, and in order to make the guide piece suitable for use at either the right or left hand side of the window, I have 30

provided a second hook 24^a upon the opposite side of the guide piece so that such hook may be in proper position for use for the aforesaid purpose should the guide piece be inverted. I have shown the slide 10 as I-shaped in cross section, but it is of course 40 obvious that other shapes may be employed.

What I claim is:

1. A clothes line extension device comprising a guide, a slide arranged to move longitudinally through the said guide, pulleys 45 carried by the said slide at opposite ends thereof, the axes of the said pulleys being parallel and lying in a single plane parallel with the slide, whereby a portion of the clothes line in passing over the same side of the said pulleys will lie in a line parallel with the said plane, and a relatively stationary pulley located intermediate the pulleys carried by the slide.

2. A clothes line extension device comprising a guide, a slide arranged to move longitudinally through the said guide, pulleys carried by the said slide at opposite ends thereof, the axes of the said pulleys being parallel and lying in a single plane parallel 50 with the slide, and a stationary pulley carried by the said guide, the axis thereof lying in the same plane with the first said pulleys.

HYLA F. MAYNES.
